(57) **CLAIM**

The ornamental design for a faceshield attachment, as shown and described.

DESCRIPTION

FIG. 1 is a perspective view, showing the new design for a faceshield attachment;

FIG. 2 is a left side view thereof, the right side being a mirror image;

FIG. 3 is a top view thereof;

FIG. 4 is a front view thereof;

FIG. 5 is a bottom view thereof; and,

FIG. 6 is an inverted rear view thereof.
